(57) **CLAIM**

The ornamental design for catalyst carrier as shown and described.

DESCRIPTION

1.1: Front top perspective view of the first embodiment of a catalyst carrier;

1.2: Rear bottom perspective view thereof;

1.3: Front elevational view thereof;

1.4: Rear elevational view thereof;

1.5: Left-side elevational view thereof;

1.6: Right-side elevational view thereof;

1.7: Top plan view thereof;

1.8: Bottom plan view thereof;

1.9: Cross-sectional taken from 1.3;

2.1: Front top perspective view of the second embodiment of a catalyst carrier;

2.2: Rear bottom perspective view thereof;

2.3: Front elevational view thereof;

2.4: Rear elevational view thereof;

2.5: Left-side elevational view thereof;

2.6: Right-side elevational view thereof;

2.7: Top plan view thereof;

2.8: Bottom plan view thereof;

2.9: Cross-sectional taken from 2.3;

3.1: Front top perspective view of the third embodiment of a catalyst carrier;

3.2: Rear bottom perspective view thereof;

3.3: Front elevational view thereof;

3.4: Rear elevational view thereof;

3.5: Left-side elevational view thereof;

3.6: Right-side elevational view thereof;

3.7: Top plan view thereof;

3.8: Bottom plan view thereof;

3.9: Cross-sectional taken from 3.3;

(Continued)

- 4.1: Front top perspective view of the fourth embodiment of a catalyst carrier; (56)
 4.2: Rear bottom perspective view thereof;
 4.3: Front elevational view thereof;
 4.4: Rear elevational view thereof;
 4.5: Left-side elevational view thereof;
 4.6: Right-side elevational view thereof;
 4.7: Top plan view thereof;
 4.8: bottom plan view thereof;
 4.9: Cross-sectional taken from 4.3;
 5.1: Front top perspective view of the fifth embodiment of a catalyst carrier;
 5.2: Rear bottom perspective view thereof;
 5.3: Front elevational view thereof;
 5.4: Rear elevational view thereof;
 5.5: Left-side elevational view thereof;
 5.6: Right-side elevational view thereof;
 5.7: Top plan view thereof;
 5.8: Bottom plan view thereof;
 5.9: Cross-sectional taken from 5.3.

The broken lines where present illustrate portions of the catalyst carrier that form no part of the claimed design.
